21 Claims. (Cl. 153—82)

1

This invention relates to manufacture in which measured quantities of work are performed and automatically controlled, in which one function of the work to be done is the displacement of a tool performing the work or the displacement of the element upon which the work is performed.

An example of such measured quantities of work is drilling holes a constant depth in parts varying in thickness and varying so that the surface in which the drill enters varies in distance from the surface of the support backing-up the drilling force.

Another example is moving an element upon which work is done, relative to the tool, so that a preselected pattern of work can be repeated at preselected intervals.

Another example is machining grooves of a fixed cross-section in a series of parts which vary in diameter.

A further example is rolling and expanding tubular elements in the tube-holes of external elements with which they are to be assembled, when the clearance between the tubes and their mating assembly member varies, and when the tube-joints are to be made to a uniform tightness, such as the tube-joints in a heat-exchanger.

One of the primary objects of this invention is to provide a method of accurately detecting when the quantity of work to be measured is to start.

Another object of this invention is to provide a method of measuring and controlling the movement of the tool so that said uniform quantities of work are produced.

A further object of this invention is to provide machines for performing the work to accomplish the objectives of the method mentioned above, so as to do the work precisely, quickly and automatically.

The preferred method of accomplishing these objectives is that which rapidly advances the tool to the position where the measured quantity of work is to be commenced and then continues the tool advance at a rate suitable for the work to be performed.

These and other objectives and advantages of this invention will become apparent from the following description when taken in connection with the accompanying drawings, in which:

Fig. 1 is a side elevation of a machine for drilling holes.

Fig. 2 shows an arrangement of hydraulic elements which may be used to control the machine shown in Fig. 1, to drill holes a constant depth in a series of parts varying in their "X" dimension.

2

Fig. 3 shows a schematic electrical diagram for operating and controlling the hydraulic equipment shown in Fig. 2.

Fig. 4 shows parts of a mechanism for moving work through a punch-press while a series of equally-spaced holes are punched.

Fig. 5 shows an arrangement of hydraulic elements which may be used to control the moving of the work shown in Fig. 4.

Fig. 6 shows a schematic electrical diagram for operating and controlling the hydraulic equipment shown in Fig. 5.

Fig. 7 shows an arrangement of machine-parts for machining grooves in a tubular element.

Fig. 8 relates to tube expanding. It shows a section through the assembly of a tube and its tube-hole with the expanding tool in the tube, taken along the line 8—8 of Fig. 10, before the tube starts to expand.

Fig. 9 is the same section shown in Fig. 8 showing, to a slightly exaggerated degree, the shape and condition of the tube when the several angularly spaced areas on the outer surface of the tube first make firm contact with the tube-hole.

Fig. 10 is the side elevation of a machine for driving the expanding tool to expand tubes into firm engagement with an external member with which the tubes are to be assembled.

Fig. 11 shows an arrangement of hydraulic elements which may be used to control the machine shown in Fig. 10.

Fig. 12 shows a schematic electrical diagram for operating and controlling the hydraulic equipment shown in Fig. 11.

Fig. 13 is a section through the machine shown in Fig. 10 in the direction of the line 13—13.

Fig. 14 is a section through the machine shown in Fig. 10 in the direction of the line 14—14.

Fig. 15 shows another combination of hydraulic elements which may be used to operate the machine shown in Fig. 10.

Fig. 16 shows a schematic electrical diagram for operating and controlling the hydraulic equipment shown in Fig. 15.

Fig. 17 shows a side elevation for another machine which may be used to drive the expander and perform the expanding operation by the method described in this invention.

Fig. 18 shows a combination of hydraulic elements for controlling and operating the machine shown in Fig. 17.

Fig. 19 shows a schematic electrical diagram for operating and controlling the hydraulic equipment shown in Fig. 18.

Fig. 20 shows a side elevation of an alternate

combination of mechanism to drive the self-feeding type of expanding tool and to perform the expanding operation by the method described in this invention.

Fig. 21 shows a side elevation of an alternate combination of mechanism to drive the expanding tool by rotating its roll-cage and to perform the expanding operation by the method described in this invention.

In current manufacturing practices there are many operations which require controlling of pre-selected measured quantities of work, and in which the magnitude of the measured quantities are changed from time to time. The examples shown and described are indicative of the types of manufacturing operations which can advantageously use this invention.

The drilling machine shown in Fig. 1 drills holes in a series of parts 11 which vary in their "X" dimension. The holes drilled by drill 12 are to be a constant depth "C" in each of the parts 11. Since "X" varies, the approach-distance to commence the drilling varies from one part to the next.

The bracket 13 which is a part of the frame 14 backs-up the work 11 while the hole is being drilled. The power unit 15 supplies the rotating force to drive the drill 12 with said force being transmitted through the spindle 16. Spindle 16 is guided in the journal in the bracket 17 attached to the frame 14. Power unit 15 is in sliding engagement with the frame 14 in such a manner that the frame 14 resists the reactive rotation of the power-unit 15 when the drill 12 is doing work.

The axial force applied to the drill 12 is supplied by the hydraulic cylinder 19 through the piston rod 18 connected to the drive-unit 15. The bracket 20 attached to the frame 14 supports the hydraulic cylinder 19, and the bracket contains a gland and guide-bearing for the piston rod 18.

From this description we see that movement of the drill 12 is proportional to the change in volume of the hydraulic fluid in front or rear of the piston in the cylinder 19.

The hydraulic fluid is pumped from the tank T1, in Fig. 2, to the four-way valve F1 by the pump P2. Valve F1 is solenoid operated by solenoid Sol F1, with the pressure-flow from line L1 to line L3 when solenoid Sol F1 is deenergized. Valve V2 is normally open and thus the drill is normally held in a retracted position.

The cycle is started by momentarily closing the push-button switch B1 in Fig. 3. The control-cylinder M1 which measures the depth of drilling is discharged and the normally-open contact LS1-1 in limit switch LS1 is held closed. Thus when the push-button B1 is closed, current flows through coil R1-C on relay R1 and energizes said relay.

Contact R1-1 closes and holds the relay R1 closed. Contacts R1-2 closes and energizes the solenoid Sol F1 thus actuating four-way valve F1. Now the pressure-flow from the pump P2 goes through line L1 to line L2. The solenoid-operated valve V1 is normally open and the hydraulic fluid flows through valve V1, on through lines L4 and L5 to the cylinder 19. As the piston in cylinder 19 moves, the exhaust oil flows through the normally-open solenoid-operated valve V2, on through the line L3 and the four-way valve F1 and returns to the tank T1.

As the piston in cylinder 19 moves, the drill advances at a given rate, as determined by the pump, and comes into contact with the work.

When the drill contacts the work, the pressure in the advance-side of the hydraulic system builds up because of the resistance to further movement of the drill 12, offered by the work 11. The pressure in line L5 increases and this increase in pressure actuates the pressure switch PS1.

The normally-open contact PS1-1, in the pressure switch PS1, closes and allows current to flow through coil R2-C on relay R2. This closes the contact R2-1 and energizes the solenoids Sol V1, Sol V2, and Sol V3 on solenoid-operated valves V1, V2, and V3 respectively. The normally-open valve V1 closes. Now the only path of flow for the fluid going to the hydraulic cylinder is through needle valve NV1. Needle valve NV1 regulates the flow of oil advancing the piston of the cylinder 19 and thus regulates the rate of advancement of the drill 12. Thus adjusting needle valve NV1 gives the desired feed-rate for performing the work.

The normally-open solenoid-operated valve V2 closes and stops the flow of the exhaust fluid returning to the tank T1. The three-way valve V3 is of such an arrangement that the normal flow is from measuring cylinder M1 to tank T1. When solenoid Sol V3 on valve V3 is energized the flow is from the line L8 to said measuring cylinder M1. Thus as the drill 12 advances and drills a hole, the exhaust oil from the cylinder 19 charges the measuring cylinder M1.

The piston of M1 rises and carries the arm 21 with it. As arm 21 rises and releases the plunger of limit switch LS1, thus operating said limit switch, the normally-open contact LS1-1, in said limit switch, is allowed to open, but since the contact R1-1 is closed, coil R1-C on relay R1 remains energized.

The area of the measuring cylinder M1 is proportional to the area of the exhaust side of the cylinder 19. Thus the movement of the arm 21 is proportional to the movement of the drill 12. By making the area of the measuring cylinder M1 a small fraction of the area of the exhaust side of the cylinder 19, the arm 21 moves in a magnified ratio to the drill 12, and the drill 12 is more accurately controlled.

The arm 21 rises until it actuates the limit switch LS2. This stops the further advancing of the drill 12 and retracts the drill 12 through the following described chain of actions. Limit switch LS2 operates and closes contact LS2-1. This energizes coil R3-C on relay R3. The normally-closed contact R3-1 on relay R3 opens and deenergizes relay R1. The normally-closed contact R3-2 opens and deenergizes relay R2.

The relay R1 deenergizes and opens the contact R1-2. This deenergizes solenoid Sol F1 on four-way valve F1. The flow pattern through valve F1 is reversed. The relay R2 deenergizes and opens contact R2-1. This deenergizes solenoids Sol V1, Sol V2, and Sol V3 on valves V1, V2, and V3 respectively. The valves V1 and V2, in their normal positions with their solenoids deenergized, are open and the hydraulic fluid flows to retract the piston in cylinder 19 and thus retract the drill, at a given rate, as determined by the pump. The normal position of the three-way valve V3, with its solenoid Sol V3 deenergized, allows the hydraulic fluid to flow from the measuring cylinder M1 to the tank T1. The spring around the piston rod in the measuring cylinder M1 provides the force to discharge the said measuring cylinder and prepare it for its next measuring stroke.

The limit switch LS2 is adjustable relative to the limit switch LS1. Thus the length of the stroke of the measuring cylinder M1 is adjustable, and thus the drilling depth "C" of the hole in the work 11 is adjusted and controlled.

Another example of controlled measured-quantities of work is illustrated in Fig. 4. Here the work consists of moving the part 25 in a series of equally-spaced steps through the punch 26 and the die 27, in which manner a series of equally-spaced holes are punched in the part 25.

To start the work, the part 25 is positioned for the first hole of the series. The pad 28 on the end of the piston rod 29 is brought to bear against the work 25, by manually bodily shifting the cylinder 30, its contained piston rod 29, and the pad 28. The punch press is started by any suitable conventional means, not shown, thus punching the first hole, and the switch S10 in Fig. 6 is closed.

Limit switch LS14 is positioned on the press so that contact LS14-1, on said switch, is closed when the punch is up. After punching the first hole, the press-ram rises, raising the punch, and limit switch LS14 is operated. Contact LS14-1 is closed. The normally-open contact LS11-1 on limit switch LS11 is closed because the measuring cylinder M11 is discharged. The current flows through the coil R11-C on relay R11.

The relay R11 being energized closes the contact R11-1 and holds itself energized. The contact R11-2 closes and energizes solenoid Sol F11A on four-way valve F11 and solenoid Sol V13 on three-way valve V13.

The four-way valve F11 is the spring-return-to-center type and is ported in such a manner that both lines L12 and L13 in Fig. 5 are blocked when the valve spool is in its central position. Energizing solenoid Sol F11A on valve F11 operates the valve so that the hydraulic fluid flows from the pump P4 through the line L11 to the line L12.

The valve V12 is normally closed and no oil flows through line L13 while the cylinder 30 is operating to space a series of holes.

The three-way valve V13 is arranged so that the normal flow is from the measuring cylinder M11 to the tank T11. However, as previously mentioned, the three-way valve V13 was operated at the same time solenoid Sol F11A on valve F11 was energized. And as the piston in the cylinder 30 advances, the exhaust oil flows to the measuring cylinder M11.

In a manner similar to that described for the measuring cylinder M1 shown in Fig. 2, the movement of arm 31 which is attached to the piston rod of the measuring cylinder M11 is proportional to the movement of the part 25. The position of the limit switch LS12 relative to the limit switch LS11 controls the spacing of the holes being punched in the part 25.

Limit switch LS12 operates when the part 25 has been moved into position for the next hole to be punched. The contact LS12-1 closes and energizes coil R13-C on relay R13. The normally-closed contact R13-1 opens to deenergize the relay R11. This deenergizes solenoid Sol F11A on valve F11 and allows the valve spool to return to its central position. Both lines L12 and L13 are blocked and the cylinder 30 is held 70 locked in position.

Deenergizing the relay R11 also deenergizes solenoid Sol V13 on three-way valve V13. Valve V13 returns to its normal position and allows the hydraulic fluid to flow from the measuring 75

cylinder M11 to the tank T11. The spring around the piston rod in the measuring cylinder M11 provides the force to discharge the measuring cylinder M11 and prepare it for its next measuring stroke.

A contact, not shown, on relay R13 controls the clutch of the punch press so that when the limit switch LS12 operates the press is operated and the next hole is punched by the punch 26. 10 Then said press operates to raise punch 26, operate limit switch LS14, and repeat the cycle. Thus a series of holes continues to be punched until the limit switch LS13 operates. The limit switch LS13 is attached to the punch press in 15 such a position that it operates after the last hole of the series to be punched in the part 25 is punched. Limit switch LS13 operates to open contact LS13-1 and stop the repeating cycle.

The piston of the cylinder 30 is retracted to 20 prepare it for the next series of spacings by closing switch S11. This energizes coil R12-C on relay R12 and closes contact R12-1. Current flowing through the contact R12-1 energizes solenoid Sol F11R on valve F11 which changes 25 the pattern of flow through valve F11 so that the pump pressure is directed to line L13, and line L12 is open to the tank T11.

The current flowing through the contact R12-1 also energizes solenoid Sol V12 and opens the 30 valve V12. This allows the hydraulic fluid to flow from line L13 to the cylinder 30 thus retracting the piston rod 29 and the pad 28. After the cylinder 30 is in its retracted position, the switch S11 is opened.

35 Another example of controlled measured-quantities of work is shown in Fig. 7. Here the part is represented as being one of a series of tubular elements in which it is desired to machine a groove. The parts in the series vary in their inside diameter, but the depth "D" of the groove in each part must be identical. Again the approach-distance varies.

The part is gripped in the chuck 43 by the 40 jaws 42. The chuck, rotating, causes the part 41 to rotate. The tool 44, properly supported by parts not shown, is moved radially relative to the work 41, by the piston rod 45 of the cylinder 46.

The steps in controlling the operation of 50 machining the groove in the part 41 are identical to those described in connection with Fig. 1 for drilling a hole a constant depth. The hydraulic equipment shown in Fig. 2 and the electrical arrangement shown in Fig. 3 illustrate the controlling of this machining operation.

A more complex example of detecting when a 55 quantity of work to be measured commences is illustrated in Fig. 8 and Fig. 9. These figures show a section through a tube 51 which is to be expanded into tight engagement in the tube-hole 52 in the external element 53. The plane of the section in both figures is on the line 8-8 as shown in Fig. 10.

The expanding tool illustrated is the conventional cage-and-roller type using a tapered mandrel. The tapered mandrel 54 advances axially to move the rollers 55 outward radially to expand the tube. The segments of the cage 56 keep the rollers properly positioned.

A rolling force is applied on the tool while it is being expanded. This rolling force causes the rollers 55 to rotate, and as soon as the rollers make contact with the tube, the expanding-tool assembly rotates about the axis of the tapered mandrel.

Fig. 8 shows the mandrel 54 advanced to bring the rollers 55 into contact with the inner surface of the tube and it illustrates the conditions at the instant said rollers and cage are forced to revolve about the axis of the mandrel. Further advancing of tapered mandrel 54 moves rollers 55 outward radially and distorts the tube.

The distorted tube has the general appearance of having bumps on its outer surface. These bumps roll about the periphery of the tube keeping their positions relative to the positions of the rollers. And the bumps move outward radially as the mandrel advances and the rollers move outward.

It is evident, from Fig. 9, that as the bumps moving outward contact the surface of the tube-hole they are restricted from further outward movement by the metal surrounding the tube-hole. This additional resistance to the outward radial movement of said bumps produces a sharp increase in the magnitude of the force required to continue the outward radial movement of the rollers producing said bumps. Thus the instant when the several angularly spaced areas of the tube outer surface make firm contact with the surface of the tube-hole is accurately detected.

The continued outward radial movement of rollers 55, produced by the continued advancing of tapered mandrel 54, produces local compressive stresses, of a high magnitude, in the tube-wall at the points where the rollers contact said tube-wall, because of the reaction provided on the outer surface of said tube-wall by the resistance-to-movement of the metal surrounding the tube-hole. The metal in the tube-wall is thinned at the points where said compressive stresses are produced.

As the above mentioned local compressive stresses are rolled around the periphery of the tube by the rolling action of the expanding tool, the tube-wall is thinned and the excess metal flows ahead of and in the direction of the rolling forces being applied, thus increasing the circumference and diameter of said tube. This thinning and enlarging action continues as long as said mandrel advances and said rolling action continues.

The effective work done on the tube portion being rolled is the work done while thinning and flowing the tube-wall to enlarge the tube circumference and bring said tube portion into tight engagement with its tube-hole. It is apparent that said effective work done on the tube portion is the quantity of work to be measured and that the true beginning point for this measured quantity of work is the instant when the several angularly spaced areas on the tube outer surface make firm contact with the surface of the tube-hole.

This invention, by using a separate source of power to advance said tapered mandrel to thus force the rollers in said expanding tool to move outward radially, in which the magnitude of said mandrel-advancing force can be measured, provides a means for quickly expanding and distorting the tube and accurately determining the axial position of said mandrel and the corresponding radial position of said rollers at the instant said angularly spaced areas on the tube outer surface make firm contact with the surface of the tube-hole.

Since the radial movement of said rollers is proportional to the axial movement of said tapered mandrel, this invention, by measuring and controlling the amount of axial advancing move-

ment of said tapered mandrel after the several angularly spaced areas on the outer surface of the tube are in firm contact with the surface of the tube-hole and while the tube-wall is being thinned, provides a means for measuring and controlling the amount of the tube-wall thinning and its proportional enlarging of said tube portion.

Experiments have proven that this method of controlling the action of the expanding tool in which the rollers of said tool are radially expanded a controlled distance after the several angularly spaced areas on the tube outer surface are in firm contact with the surface of the tube-hole produces the correct amount of thinning of said tube-wall and enlarging of the circumference of said tube so that tube-joints are made uniformly tight regardless of the usual variations encountered in normal manufacturing practices. These usual variations are the variations in tube-hole size, tube O. D., and tube-wall thickness.

Fig. 10 shows a machine for driving and controlling the expanding tool to perform the tube expanding operation by the method set forth in this invention. Here the cage 56 and the rollers 55 are shown in the tube 51 in the tube-sheet 53. The mandrel 54 is shown in its retracted position.

The cage 56 is confined in a rotatable manner in the thrust-sleeve 57 which confines a shoulder on the cage between a series of balls 58 and a lock-ring 59. The thrust-sleeve 57 connects to a coupler 60 fastened to the front frame-member 61 of the machine. Thus the cage-and-roller assembly is supported in a fixed axial position relative to the outer frame of the machine.

Part 63 represents the power unit supplying the rotary force to the tapered mandrel 54. The said rotary force is transmitted through the drive spindle 69. Spindle 69 is slidably supported in the frame-member 61. Power unit 66 is in slideable engagement with the outer frame of the machine.

Power unit 68 connects to the piston rod 71 of the hydraulic cylinder 67. Thus the tapered mandrel 54 is in a fixed axial relation with the piston 70 of the cylinder 67, and the mandrel 54 moves with the piston 70.

The reaction on the cylinder 67 to the force applied on the piston 70 is transmitted to the cage-and-roller assembly through the rear frame-member 62, the tie-rods 63-66, the front frame-member 61, the coupler 60 and the thrust-sleeve 57. Thus the cage, and the rollers, of the expanding tool are in a fixed relation with the cylinder 67, and movement of the piston 70 relative to the cylinder 67 causes a like amount of axial movement between the rollers 55 and the tapered mandrel 54.

The section shown in Fig. 13, taken on the line 13-13 of Fig. 10 shows how the tie-rods 65 and 66 confine the lug 72 on the case of the power unit 68. Thus the reactive rotary force imposed on the case of the power unit 68 is transmitted to the outer frame of the machine.

The section shown in Fig. 14, taken on the line 14-14 of Fig. 10, shows the handles 74 and 75 which the operator may use to hold the machine and resist the reactive rotary force. The lifting lug 73 may be attached to a supporting cable, not shown, and used to support the machine.

The axial movements of the mandrel, as the machine expands a tube, may be powered and controlled with the arrangement of hydraulic

components shown in Fig. 11. This arrangement of hydraulic elements is similar to that shown in Fig. 2 for controlling the drilling operation in Fig. 1.

The arrangement of the hydraulic components in Fig. 11 adds a solenoid-operated normally-open valve V24 to the arrangement shown in Fig. 2. The schematic arrangement of the electrical equipment for controlling the hydraulic assembly shown in Fig. 11 has a time-delay relay TD1 replacing the relay R3 shown in Fig. 3. These changes over the arrangement shown in Fig. 2 and Fig. 3 give a controlled dwell interval at the conclusion of the metal-thinning work period being measured.

The dwell in this tube expanding-and-rolling cycle permits the rolling action to continue without any further outward radial movement of the rollers. Thus the metal-thinning action is allowed to gradually cease and the stresses around all parts of the periphery of the tube-joint are equalized before the expanding tool is retracted and withdrawn from the tube-joint.

The hydraulic fluid is pumped from tank T21, in Fig. 11, to four-way valve F21 by pump P11. Valve F21 is solenoid operated with the pressure-flow from the pump through valve F21 and through normally-open valve V22 to the return connection on cylinder 67 when solenoid Sol F21 of said valve F21 is deenergized. Thus piston 70, of cylinder 67, and mandrel 54 of the expanding tool are normally held back in the retracted position.

The cycle is started by momentarily closing push-button switch B21 in Fig. 12. The control-cylinder M23, which measures the further advance of the mandrel after the condition shown in Fig. 3 is established, is discharged and normally-open contact LS21-1 on limit switch LS21 is held closed. Thus when push-button B21 is closed, current flows through coil R21-C on relay R21.

Contact R21-1 holds relay R21 closed. Contact R21-2 energizes solenoid Sol F21 and actuates four-way valve F21. Now the pressure-flow from pump P11 goes through the advance side of the hydraulic circuit, through normally-open valve V24, and to the advance connection on cylinder 67. As piston 70 in cylinder 67 advances, the exhaust oil flows through normally-open valve V22, through valve F21, and back to tank T21.

As piston 70 in cylinder 67 advances, mandrel 54 of the expanding tool advances at the given rate, as determined by the pump, and causes rollers 55 to move outward radially. As the mandrel advances, the expanding tool and the tube being rolled are relatively-quickly expanded through the condition shown in Fig. 8 to the condition shown in Fig. 9. At the instant the condition shown in Fig. 9 is established, the force required to continue the advance of the mandrel increases, as previously described, and the pressure in the advance-side of the hydraulic system increases and actuates pressure switch PS21.

At this moment normally-open contact PS21-1, in pressure switch PS21, closes and since contact R21-3 is being held closed, current flows through coil R22-C on relay R22. This closes contact R22-1 and energizes the solenoids Sol V21, Sol V22, and Sol V23 on the solenoid-operated valves V21, V22, and V23 respectively. The normally-open valve V21 closes. Then the only path of flow for the fluid going to hydraulic cylinder 67 is through needle valve NV21. Needle valve NV21 regulates the flow of oil advanc-

ing piston 70 of cylinder 67 and thus regulates the rate of advancement of mandrel 54 during the portion of the advance which produces the tube-wall thinning and its consequent tube-enlarging. Obviously, the preferred setting for NV21 is that which advances the mandrel, and thus expands the rolls, as fast as the metal thinning and flowing action can be performed. Thus the preferred setting for NV21 gives a mandrel-advance rate proportional to the rate of plastic-flow for the particular type of metal in the tubes being rolled.

Also at this instant, the normally-open solenoid-operated valve V22 closes and stops the flow of the exhaust fluid returning to tank T21. The three-way valve V23 is of such an arrangement that the normal flow is from measuring cylinder M23 to tank T21. When solenoid Sol V23 on valve V23 is energized the flow is from cylinder 67 through the return circuit of the hydraulic system through valve V23 and to measuring cylinder M23. Thus as mandrel 54 advances and causes the expanding tool to thin and enlarge the tube, the exhaust fluid from cylinder 67 charges measuring cylinder M23.

The piston of M23 rises and carries arm 81 with it. Limit switch LS21 operates and opens normally-open contact LS21-1, but since contact R21-1 is closed, coil R21-C on relay R21 remains energized.

The area of measuring cylinder M23 is proportional to the area of the exhaust side of cylinder 67. Thus the movement of arm 81 is proportional to the movement of mandrel 54. By making the area of measuring cylinder M23 a small fraction of the area of the exhaust side of cylinder 67, arm 81 moves in a magnified ratio to mandrel 54, and the mandrel is more accurately controlled. This, of course, more accurately measures and controls the tube-wall thinning and tube-enlarging action of the tool.

Arm 81 rises until it actuates limit switch LS22. This stops the further advancing of mandrel 54 through the following described series of actions. Limit switch LS22 operates and closes contact LS22-1. This energizes coil TD1-C on time-delay relay TD1, starting the time-delay interval. Contact LS22-2 closes and energizes solenoid Sol V24 on solenoid-operated valve V24. Normally-open valve V24 closes. Thus the hydraulic fluid can no longer flow to cylinder 67. The fluid between valve V24 and piston 70 in cylinder 67 is trapped.

As soon as limit switch LS22 is actuated by arm 81, the housing of said switch physically stops the further advancing of arm 81, and the advancing of the piston in measuring cylinder M23 is stopped. Since the only path-of-flow for the hydraulic fluid being exhausted from cylinder 67 is into measuring cylinder M23, the fluid on the exhaust side of the piston is trapped. The piston 70 of cylinder 67 is held in a fixed position, thus holding mandrel 54 in a fixed axial position. Thus, as previously described, the tube-wall thinning action is gradually stopped. This condition exists until the end of the time-delay interval. Then time-delay relay TD1 acts and normally-closed contact TD1-1 is opened.

When contact TD1-1 opens, relay R21 is deenergized. Contact R21-1 opens. Contact R21-2 opens and deenergizes four-way valve F21. The flow pattern through valve F21 is reversed. Contact R21-3 opens and deenergizes coil R22-C on relay R22. Contact R22-1 opens and deenergizes the solenoids Sol V21, Sol V22, and Sol

11

V23 on valves V21, V22, and V23 respectively. Valves V21 and V22, in their normal positions with their solenoids deenergized, are open so the hydraulic fluid may flow through them. The normal position of the three-way valve V23, with its solenoid deenergized, allows the hydraulic fluid to flow from measuring cylinder M33 to tank T21. The spring around the piston rod in measuring cylinder M23 provides the force to discharge said measuring cylinder and prepare it for its next measuring stroke.

As measuring cylinder M23 starts to discharge, arm 81 moves downward with the piston of said measuring cylinder. As arm 81 retracts, limit switch LS22 is released and contact LS22-2 opens to deenergize solenoid Sol V24 of valve V24. Valve V24 returns to its normally-open position and the hydraulic circuit is now open to allow piston 70 in cylinder 67 to retract, thus reTRACTING the expanding tool. The automatic cycle of expanding and rolling a tube is completed.

Limit switch LS22 is adjustable relative to limit switch LS21. Thus the length of the stroke of measuring cylinder M23 is adjustable, and thus the amount of the tube-wall thinning and the tube enlarging is adjusted and controlled.

The handle 75, as shown in Fig. 14, on the frame of the expanding machine may be made to rotate with a switch for controlling the commencing of the expanding cycle mounted inside the rotating handle in such a manner that the cam action occurring when the handle 75 is rotated opens and closes the switch. Thus the handle 75 becomes a live-handle controlling the acting of the machine.

A second switch in the live handle 75, together with additional electrical components added to the electrical arrangement of Fig. 12, will provide a control for stopping the automatic cycle and retracting the expanding tool at the will of the operator.

Another arrangement of the hydraulic elements for operating the machine shown in Fig. 10, is shown in Fig. 15. In this arrangement, the detecting of the beginning of the useful work to be measured is identical to that shown in Fig. 11, but the measuring of the useful work is performed by a combined measuring and pressure-boosting cylinder M33. The measured quantity of fluid is that being pumped into the hydraulic cylinder 67, of Fig. 10.

In the arrangement in Fig. 15, the pump P15 pumps the hydraulic fluid to the solenoid-operated four-way valve F31 through line L31. The solenoid-operated valve F35 is a double two-way valve which is normally closed.

Closing the switch B31 in Fig. 16 starts the cycle. Coil R31-C on relay R31 is energized. The contact R31-2 on relay R31 energizes solenoid Sol F31 on valve F31. The pressure-flow is now to line L32, through the check-valves CV2 and CV3 and on to the cylinder 67, of Fig. 10.

The exhaust flow from the cylinder 67 is through the check valve CV4, through line L33, and the four-way valve F31 to the tank T31. When the several angularly spaced areas on the tube outer surface make firm contact with the tube-hole, the pressure switch PS31 operates and closes contact PS31-1. This energizes solenoid Sol F35 on valve F35 and allows flow to the booster-measuring cylinder M33.

The flow into the cylinder M33 is through the needle valve NV31, which serves to regulate and control the rate of advancing of the booster cylinder and thus regulate and control the advance

12

of the tapered mandrel 54 to give a rate suitable for thinning the tube metal. The flow entering the cylinder M33 causes the piston assembly to rise. Since the pressure is under the large-area piston, a proportionally higher pressure is exhausted from the small-diameter cylinder into line L36.

This high-pressure in line L36 is blocked in the one direction by the check valve CV2. The only path of flow available is through the check valve CV3 and into cylinder 67. Arm 91 moves proportionally to piston 70 and the tapered mandrel 54 of Fig. 10.

Limit switch LS32 operates when the preselected amount of measured travel for the arm 91 occurs. The contact LS32-1 opens and deenergizes solenoid Sol F35 on valve F35. Valve F35 closes and blocks both lines L34 and L35 in the low-pressure compartment of the booster-measuring cylinder M33. The contact LS32-2 closes and actuates coil TD31-C on time-delay relay TD31. This gives a dwell during the time-delay interval. During the dwell, the tapered mandrel 54 is held in a fixed axial position. The rolling action continues and equalizes the stresses around the periphery of the tube-joint.

At the end of the time-delay interval the contact TD31-1 opens and deenergizes coil R31-C on relay R31. This deenergizes solenoid Sol F31 on four-way valve F31 and reverses the flow through the valve. Another contact on the time-delay relay TD31, not shown, opens the valve F35 by energizing solenoid Sol F35 on valve F35.

Needle valve NV32 serves as a restriction in line L33. Thus the flow goes to the booster-measuring cylinder M33. The piston assembly in cylinder M33 retracts with the booster-pressure flow going to cylinder 67 through the check valve CV6.

The pressure and flow retracting the piston 70 of cylinder 67 actuates the pilot-operated two-way valve PV1 and allows the oil being exhausted from cylinder 67 to flow direct to the tank T31.

After the measuring cylinder M33 is retracted, the fluid continues to flow to cylinder 67 through the needle valve NV32. A time-delay relay, not shown, operates to deenergize solenoid Sol F35 on valve F35, and the circuit is ready for the next cycle.

Fig. 17 illustrates another type of mechanism, within the scope of this invention, which expands and rolls tubes into tight engagement in tube-holes. Here the detecting of the increase in force which indicates the commencing of the useful work is by mechanical means. And the preselected measuring and controlling of the displacement of the tool performing the work is by electro-mechanical means.

Another manner in which the machine shown in Fig. 17 differs from the one heretofore described is that the force advancing the tool to bring it into working position is applied only during the approach-interval of the cycle. As soon as the useful work commences, the external force applied to advance the mandrel is discontinued, and the power unit 163 is allowed to float in an axial direction while the self-feeding effect of the tool produces the additional expansion which thins and expands the tube into tight engagement in the tube-hole.

In this machine, the expander cage 153 confines the rollers 155 at an axial-angle with the axis of the tool. This gives the expanding tool a self-feeding effect in that the rotary force applied on the tapered mandrel 54 together with

the frictional-gripping of said tapered mandrel by the rollers 155 which is caused by the inward radial reactive force on the rollers, causes the tapered mandrel to screw itself into the assembly in much the same fashion as a woodscrew advances into wood.

The expanding tool is connected to the front frame-member 161 of the machine by the thrust-sleeve 157 and the coupler 169. The front frame-member 161 is connected to the hydraulic cylinder 167 by the tie rods 163—166, and the rear frame-member 162.

The power unit 168 applies the rotary force to the tapered mandrel 154 through the drive spindle 169. The power unit 168 is in slidable engagement with the outer frame assembly and it is prevented from rotating in the outer frame by the lug 168', attached to the power-unit case, being confined between the tie rods 165 and 166.

The force on the piston 170 of cylinder 167 causing the tapered mandrel 154 to advance is transmitted to the power unit 168 through the thrust sleeve 171, the flange 174 and the spring 175. The rod 172 which is in slidable engagement with the thrust sleeve 171, piston 170, thrust sleeve 171, and flange 174, is solidly connected to the case of the drive unit 168.

The rod 172 serves to guide this rear assembly, to guide the spring 175, and to provide vertical support for the drive unit 168. The sleeve 171 extending through the rear end of the cylinder 167 serves to bring the adjusting nut 173 outside of the hydraulic cylinder.

Turning the nut 173 on the rod 172 adjusts the preload in the spring 175. Thus spring 175 can be preloaded so that there is no decrease in length of the spring until the axial force on the tapered mandrel 154 exceeds the preload setting. By setting the preload on the spring 175 and adjusting the screw 184, the machine is set to operate the limit switch LS41 at any selected force within the range of the spring. Thus the increase in the linear force advancing said mandrel which occurs the instant the tube is expanded sufficiently to bring several angularly spaced areas of the outer surface of the tube into firm contact with the defining wall of its tube-hole is detected.

The adjusting screw 185 serves to prevent over-travel which could damage limit switch LS41.

The housing 180 is in slidable engagement with the tierod 163. The clamp pad 181 is enclosed in the housing 180 in such a manner that when pad 181 is forced against tierod 163, the housing 180 comes into fixed engagement with said tierod. The solenoid 182 supplies the force for clamping the pad 181 to the tierod 163.

The guide-rod 179 is in slidable engagement with base member 176, attached to the case of power unit 168, and guide rod 179 is attached to housing 180. Thus the assembly of guide rod 179 and housing 180 forms a slide member slidable relative to tierod 163 or slidably relative to base member 176. Said slide member is normally pushed away from base member 176 by the compression spring 183 with such pushing-away movement being limited by the flange 188 on guide rod 179. Thus in its normal condition, not clamped to tie rod 163, said slide member moves relative to tierod 163, with base member 176 and power unit 168.

When the housing 180 is clamped to the tierod 163, base member 176 approaches the housing 180, compressing the spring 183, as mandrel 154 advances and pulls power unit 168 forward. Thus the relative movement between base member 176

and said slide member is a measure of the mandrel axial advancing movement. Limit switch LS42 is attached to base member 176. The adjusting screw 187 forms an extension of the guide-rod 179, and it is in line with the plunger on the limit switch LS42.

After base member 176 moves relative to said slide member a sufficient amount, the screw 187 operates the limit switch LS42. By controlling solenoid 182 so that it clamps said slide member to the tierod 163 at the instant the several angularly spaced areas on the outer surface of the tube are brought into firm contact with the defining surface of the tube-hole, the relative movement between the bracket 176 and the slide member serves to measure the advancement of the tapered mandrel 154 during the time the expanding tool is thinning the tube wall.

An arrangement of hydraulic components which may be used to operate the machine shown in Fig. 17 is shown in Fig. 18. Here the solenoid-operated four-way valve F41 is the spring-return-to-center type with the porting arranged so that when the valve spool is in its central position, both lines to the cylinder are open to the tank. Piston 170 in cylinder 167 is in a floating condition when valve F41 is in neutral.

Pump P18 pumps the hydraulic fluid through line L41 to the four-way valve F41. Closing the switch B41 energizes coil R41-C on relay R41 which in turn energizes solenoid Sol F41A on valve F41. This operates the four-way valve so that the pressure-flow is through line L41 to line L42 and on to the cylinder 167. The tapered mandrel 154 advances.

The tapered mandrel 154 advances at a relatively rapid given rate until the several points on the outer surface of the tube contact the tube-hole, as shown in Fig. 9, when the resistance to further advancing of the mandrel 154 increases. This increased resistance compresses spring 175 and operates the limit switch LS41. Obviously, the piston 170 must act to advance the mandrel at a rate faster than the mandrel is advanced by the self-feeding action of the tool in order to produce a linear force acting to compress the spring 175.

Limit switch LS41 operating, in turn energizes relay R42 and deenergizes solenoid Sol F41A on four-way valve F41. The valve spool in valve F41 returns to center and allows piston 170 in cylinder 167, the power unit 168, and the tapered mandrel 154 of Fig. 17, to float as a unit.

The relay R42 also energized the coil 182-C of solenoid 182 on the clamp unit 180 so that the measuring of the additional advancement of the tapered mandrel 154 commences.

The axial-power assembly being in a floating condition, the only advancement of the mandrel 154 is that caused by the self-feeding effect of the expanding tool. The rotating force continues, and the expanding tool rotates and expands the tube, pulling the mandrel 154 forward and moving the limit switch LS42 relative to the stop screw 187.

The expanding action continues until the plunger on the limit switch LS42 contacts the screw 187 and limit switch LS42 operates. Then switch LS42 operates relay R43 which energizes solenoid Sol F41R on four-way valve F41 and deenergizes the coil 182-C of solenoid 182 on clamp unit 180. The circuiting of the four-way valve F41 is reversed to give flow and pressure retracting the piston 170 in the cylinder 167.

Piston 170 acting through thrust-sleeve 171,

15

nut 173, rod 172, power unit 168, and drive spindle 169, transmits the retracting force to the mandrel 154, pulls the mandrel back to retract the expanding tool and thus ends the expanding operation.

While, for the sake of illustration, the devices are herein shown and described in connection with the performing of certain types of work, it will be apparent to those skilled in the art that the principles of the invention may be applicable in other combinations in these same operations, and applicable in other operations and with various types of tools.

The hydraulic system in Fig. 10 and Fig. 17 may be replaced by some other type of power device such as the electric motor arrangement shown in Fig. 20. The mechanism shown in Fig. 20 is a duplicate of Fig. 17 with two exceptions. Fig. 20 shows an electric motor supplying the linear force advancing the mandrel, and it shows a hydraulic-powered clamp for clamping the measuring unit to the frame.

The electric motor 367 is attached to rear frame member 162 and positioned so that gear 370, on the shaft of said motor 367, makes proper engagement with gear-rack 377. Gear-rack 377 replaces thrust sleeve 177, and thrust sleeve 171, of Fig. 17, and, in an identical manner, transmits the force produced by motor 367. Rod 172, flange 174, and the other parts acting to transmit and control the linear forces moving the mandrel are as described for Fig. 17.

The hydraulic cylinder-and-piston assembly 382, in Fig. 20, replaces the solenoid 182, in Fig. 17. Pressure applied through line 399 produces a force acting on pad 181 to bring housing 180 into fixed engagement with tierod 163 to thus cause the actions as described in connection with Fig. 17.

The energy-supply circuitry controlling the energizing of electric motor 367, in Fig. 20, acts identically to the hydraulic system energizing the hydraulic power device in Fig. 17 so that the apparatus of Fig. 20 performs in the same manner and produces the same results as are described for Fig. 17.

It is apparent that the increase in linear force axially advancing mandrel 154 which occurs the instant the tube portion is expanded sufficiently to bring the several angularly spaced areas of the tube outer surface into firm contact with the defining wall of its tube-hole, and which compresses spring 175, also increases the energy-input demanded by electric motor 367. Thus it is apparent that the increase in linear force sensed by the force-sensitive device illustrated in Fig. 20 could be equally sensed by a conventional current-sensitive device connected into the electrical circuit to motor 367, and set to be actuated when the proper current value is developed, and whereby, when actuated, said current-sensitive device performs functions similar to those performed by switch LS41, of Fig. 17.

Another arrangement of apparatus, within the scope of this invention, is illustrated in Fig. 21. This mechanism is identical to that shown in Fig. 10, except that, in Fig. 21, the roll-cage 356, of Fig. 10, is power rotated and, therefore, the power unit 68, of Fig. 10, remains in a fixed axial position, relative to said roll-cage and the apparatus frame.

The mechanism shown in Fig. 21 has a power unit 368 transmitting the rotary force to roll-cage 356 by means of drive spindle 369. Power unit 368 is attached to front frame-member 61,

and roll-cage 356 is connected to drive spindle 369, thus supporting the cage-and-roller assembly in a fixed axial position relative to the apparatus frame while said cage is being power rotated.

In Fig. 10, the thrust reaction between the mandrel and roll-cage produced by the linear force being applied, is transmitted to frame member 61 by means of bearing 58, thrust-sleeve 57, and coupler 60. The said thrust reaction, in Fig. 21, is transmitted to frame 61 by means of drive spindle 369, the bearings in power unit 368, which support spindle 369, the case of power unit 368 and the connecting means attaching said power unit to frame member 61.

The mandrel 54, in Fig. 21, connects directly to piston rod 371, with piston rod 371 axially sliding through hollow sleeve-like spindle 369 and through the suitable opening provided in the case of power unit 368.

The power-rotated roll-cage 356 acts to push the rolls by means of the contact surface of the ligaments of said roll-cage bearing against said rolls, to thus rotate said rolls about mandrel 54. As the rolls rotate about said mandrel, they are in contact with the surface of the mandrel and the inner surface of the tube portion being expanded and the relative movement between the rolls and said surfaces is partly rolling and partly sliding.

The circuitry used to power and control the mechanism shown in Fig. 10, as shown in Fig. 11 and Fig. 12, can be used to power and control the mechanism shown in Fig. 21. The actions and results obtained when said circuitry operates the Fig. 21 mechanism are as described for Fig. 10.

While the invention has been described with reference to the particular devices illustrated, it is to be appreciated that it is not so limited. It is rather of a scope commensurate with the scope of the subjoined claims.

What I claim as my invention is:

1. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, axially movable, mandrel; a frame to which said roll-cage is rotatably connected, a powered tool-rotating unit carried by the frame, a power device adapted to produce a linear force acting to advance the mandrel axially, at a given rate, the power device producing the linear force being so connected to said frame that the reaction to the linear force advancing the mandrel is resisted by said frame, a force-sensitive device actuated by the increase in the linear force axially advancing the mandrel which occurs the instant the tube portion is expanded sufficiently to bring several angularly spaced areas of the tube outer surface into firm contact with the defining wall of its tube-hole, thus detecting the start of the tube-wall thinning action, a measuring device started into actuation by the force-sensitive device at the instant of such detection and which, by its actuation, measures the further axial advancing movement of the mandrel, and means responsive to the measuring device and acting to limit said further axial advancing movement of the mandrel whereby the tube wall is thinned a preselected measured amount and said portion of the tube is circum-

ferentially enlarged sufficiently to give it the pre-selected tightness in its tube-hole.

2. An apparatus as in claim 1; wherein said last named means subsequently acts to cause the application of a linear force axially retracting said mandrel.

3. An apparatus as in claim 1; including means responsive to said measuring device and applying a linear force axially retracting said mandrel after the tube portion is so enlarged.

4. An apparatus as in claim 1; including means responsive to said measuring device, acting after the tube portion is so enlarged, continuing the rolling action with no change in axial position of said mandrel for a controlled interval of time, and thereafter applying a linear force axially retracting said mandrel.

5. An apparatus as in claim 1; including means actuated by said force-sensitive device at the instant of such detection and operable to regulate the rate of mandrel advance during its said further axial advancing movement.

6. An apparatus as in claim 1; wherein said given rate of axial advancing of the mandrel is relatively rapid, and wherein there is included means actuated by said force-sensitive device at the instant of such detection and operable to decrease the rate of mandrel advance during its said further axial advancing movement.

7. An apparatus as in claim 1; wherein said power device is an hydraulic cylinder-and-piston motor mounted on said frame.

8. An apparatus as in claim 7; wherein said hydraulic motor responds to said measuring device, after the tube portion is so enlarged, in a manner to apply a linear force axially retracting said mandrel.

9. An apparatus as in claim 7; wherein said hydraulic motor responds to said measuring device, after the tube portion is so enlarged, and after the rolling action is continued with no change in axial position of said mandrel for a controlled interval of time, in a manner to apply a linear force axially retracting said mandrel.

10. An apparatus as in claim 1; wherein at least some of said rolls are cocked to effect a self-feeding of the mandrel, and wherein there is included means actuated by said force-sensitive device at the instant of such detection and operable to deenergize said power device whereby the self-feeding action of said tool produces said further axial advancing movement of the mandrel.

11. An apparatus as in claim 10; wherein said power device is an hydraulic cylinder-and-piston motor mounted on said frame.

12. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, rotatable and axially movable, mandrel; a frame to which said roll-cage is rotatably connected, a powered tool-rotating unit for rotating the mandrel and having an element axially movable with said mandrel, said unit carried by the frame, a power device adapted to produce a linear force transmitted by means of said element to advance said mandrel axially, at a given rate, the power device producing the linear force being so connected to said frame that the reaction to the linear force advancing the mandrel is resisted by said frame, a force-sensitive de-

vice actuated by the increase in the linear force axially advancing the mandrel which occurs the instant the tube portion is expanded sufficiently to bring several angularly spaced areas of the tube outer surface into firm contact with the defining wall of its tube-hole, thus detecting the start of the tube-wall thinning action, a measuring device started into actuation by the force-sensitive device at the instant of such detection and which, by its actuation measures the further axial advancing movement of the mandrel, and means responsive to the measuring device and acting to limit said further axial advancing movement of the mandrel whereby the tube wall is thinned a preselected measured amount and said portion of the tube is circumferentially enlarged sufficiently to give it the preselected tightness in its tube-hole.

13. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, non-rotatable and axially movable, mandrel; a frame to which said roll-cage is rotatably connected, a powered tool-rotating unit for rotating the roll-cage, said unit carried by the frame, a power device adapted to produce a linear force acting to advance the mandrel axially, at a given rate, the power device producing the linear force being so connected to said frame that the reaction to the linear force advancing the mandrel is resisted by said frame, a force-sensitive device actuated by the increase in the linear force axially advancing the mandrel which occurs the instant the tube portion is expanded sufficiently to bring several angularly spaced areas of the tube outer surface into firm contact with the defining wall of its tube-hole, thus detecting the start of the tube-wall thinning action, a measuring device started into actuation by the force-sensitive device at the instant of such detection and which, by its actuation, measures the further axial advancing movement of the mandrel, and means responsive to the measuring device and acting to limit said further axial advancing movement of the mandrel whereby the tube wall is thinned a preselected measured amount and said portion of the tube is circumferentially enlarged sufficiently to give it the preselected tightness in its tube-hole.

14. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, rotatable and axially movable, mandrel; a frame to which said roll-cage is rotatably connected, a powered tool-rotating unit for rotating the mandrel and having an element axially movable with said mandrel, said unit carried by the frame, a hydraulic cylinder-and-piston motor adapted to produce a linear force transmitted by means of said element to advance said mandrel axially, at a given rate, the hydraulic motor being so connected to said frame that the reaction to the linear force advancing the mandrel is resisted by said frame, a measuring device comprising a cylinder-and-piston assembly and an electrical switch attached to the cylinder with the switch arranged so as to be operated

when the piston has moved, relative to said cylinder, to advance a preselected distance, with said switch, when operated, causing an action whereby the mandrel advancing movement is limited, said measuring device being connected into the fluid circuit for said hydraulic motor so that the fluid discharged from said motor when its acts to axially-advance said mandrel is directable to said measuring device to produce an advancing movement of said measuring-device piston which is proportional to the advancing movement of said mandrel to thus measure the axial advancing movement of said mandrel, a force-sensitive device consisting of a pressure-actuated switch arranged so as to be responsive to the fluid pressure acting on said hydraulic motor to produce the mandrel-advancing movement, with said switch operating, when the force-sensitive device is actuated, to actuate means whereby said measuring device is started into actuation, with said force-sensitive device being actuated by the increase in said fluid pressure producing the linear force advancing the mandrel which occurs the instant the tube portion is expanded sufficiently to bring several angularly spaced areas of the tube outer surface into firm contact with the defining wall of its tube-hole, thus detecting the start of the tube-wall thinning action, means actuated by the force-sensitive device at the instant of such detection and regulating the rate of advancing of said mandrel during its further advancing movement, and means responsive to the measuring device and acting to limit said further axial advancing movement of the mandrel whereby the tube wall is thinned a preselected measured amount and said portion of the tube is circumferentially enlarged sufficiently to give it the preselected tightness in its tube-hole.

15. An apparatus as in claim 14; including means responsive to said measuring device, acting after the tube portion is so enlarged, and powering said hydraulic motor to produce a linear force axially retracting said mandrel.

16. An apparatus as in claim 14; wherein said hydraulic motor responds to said measuring device, after the tube portion is so enlarged, and after the rolling action is continued with no change in axial position of said mandrel for a controlled interval of time, in a manner to apply a linear force axially retracting said mandrel.

17. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, rotatable and axially movable, mandrel; a frame to which said roll-cage is rotatably connected, a powered tool-rotating unit for rotating the mandrel and having an element axially movable with said mandrel, said unit carried by the frame, a hydraulic cylinder-and-piston motor adapted to produce a linear force transmitted by means of said element to advance said mandrel axially, at a given rate, the hydraulic motor being so connected to said frame that the reaction to the linear force advancing the mandrel is resisted by said frame, a measuring device comprising a cylinder-and-piston assembly and an electrical switch attached to the cylinder with the switch arranged so as to be operated when the piston has moved, relative to said cylinder, to advance a preselected distance,

with said switch when operated, causing an action whereby the mandrel advancing movement is limited, said measuring device being connected into the fluid circuit for said hydraulic motor so that the fluid discharged from the cylinder of said measuring device, when its piston advances, powers said hydraulic motor to produce a proportional advancing movement of said mandrel to thus provide a measure of the axial advancing movement of said mandrel, a force-sensitive device consisting of a pressure-actuated switch arranged so as to be responsive to the fluid pressure acting on said hydraulic motor to produce the mandrel-advancing movement, with said switch operating, when the force-sensitive device is actuated, to actuate means whereby said measuring device is started into actuation, with said force-sensitive device being actuated by the increase in said fluid pressure producing the linear force advancing the mandrel which occurs the instant the tube portion is expanded sufficiently to bring several angularly spaced areas of the tube outer surface into firm contact with the defining wall of its tube-hole, thus detecting the start of the tube-wall thinning action, means actuated by the force-sensitive device at the instant of such detection and regulating the rate of advancing of said mandrel during its further advancing movement, and means responsive to the measuring device and acting to limit said further axial advancing movement of the mandrel whereby the tube wall is thinned a preselected measured amount and said portion of the tube is circumferentially enlarged sufficiently to give it the preselected tightness in its tube-hole.

18. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, rotatable and axially movable, mandrel, with at least some of said rolls cocked to effect a self-feeding of the mandrel; a frame to which said roll-cage is rotatably connected, a powered tool-rotating unit for rotating the mandrel and having an element axially movable with said mandrel, said unit carried by the frame, a power device adapted to produce a linear force transmitted by means of said element to advance said mandrel axially, at a given rate, the power device producing the linear force being so connected to said frame that the reaction to the linear force advancing the mandrel is resisted by said frame, a measuring device comprising a base member attached to said element, a slide member resiliently slidable relative to the base member and slidably coordinated with said apparatus frame, an electrical switch attached to said base member so as to be operated when said base member has advanced, relative to said slide member, a preselected measured distance, with said switch, when operated, causing an action whereby the mandrel advancing movement is limited, and a powered clamp attached to said slide member so that, when actuated, it clamps said slide member to said frame to produce a relative advancing movement between said base member, advancing with said element, and said slide member which is a measure of the advancing movement of said mandrel, a force-sensitive device having a resilient member connected to said element so that said linear force advancing

said mandrel acts on the resilient member, and an electrical switch which, when operated, actuates means whereby said powered clamp is actuated, with said switch arranged in combination with said resilient member and said element so that the increase in the linear force advancing said mandrel which occurs the instant the tube portion is expanded sufficiently to bring several angularly spaced areas of the tube outer surface into firm contact with the defining wall of its tube-hole causes the resilient member to actuate said electrical switch, thus detecting the start of the tube-wall thinning action, means actuated by the force-sensitive device at the instant of such detection and operable to de-energize said power device whereby the self-feeding action of said tool produces the further axial advancing movement of said mandrel, and means responsive to the measuring device and acting to limit said further axial advancing movement of the mandrel whereby the tube wall is thinned a preselected measured amount and said portion of the tube is circumferentially enlarged sufficiently to give it the preselected tightness in its tube-hole.

19. An apparatus as in claim 18; wherein said power device is an hydraulic cylinder-and-piston motor mounted on said frame.

20. An apparatus for expanding a lineal portion of a tube, to a preselected tightness, in its tube-hole, comprising a roller-type expanding tool having a roll-cage, a plurality of angularly spaced expanding-rolls radially movable in the roll-cage, with said roll-cage and said expanding-rolls rotatably mounted about a tapered, non-rotatable and axially movable, mandrel; a frame to which said roll-cage is rotatably connected, a powered tool-rotating unit for rotating the roll-cage, said unit carried by the frame, a hydraulic cylinder-and-piston motor adapted to produce a linear force acting to advance the mandrel axially, at a given rate, the hydraulic motor being so connected to said frame that the reaction to the linear force advancing the mandrel is resisted by said frame, a measuring device comprising a cylinder-and-piston assembly and an electrical switch attached to the cylinder with the switch arranged so as to be operated when the piston has moved, relative to said cylinder, to advance a preselected distance, with said switch, when operated, causing an action whereby the mandrel advancing movement is limited, said measuring device being connected into the fluid circuit for said hydraulic motor so that the fluid discharged from said motor when it acts to axially-advance said mandrel is directable to said measuring device to produce an advancing movement of said measuring-device piston which is proportional to the advancing movement of said mandrel to thus measure the axial advancing movement of said mandrel, a force-sensitive device consisting of a pressure-actuated switch arranged so as to be responsive to the fluid pressure acting on said hydraulic motor to produce the mandrel-advancing movement, with said switch operating, when the force-sensitive device is actuated, to actuate means whereby said measuring device is started into actuation, with said force-sensitive device being actuated by the increase in said fluid pressure producing the linear force advancing the mandrel which occurs the instant the tube portion is expanded sufficiently to bring several

angularly spaced areas of the tube outer surface into firm contact with the defining wall of its tube-hole, thus detecting the start of the tube-wall thinning action, means actuated by the 5 force-sensitive device at the instant of such detection and regulating the rate of advancing of said mandrel during its further advancing movement, and means responsive to the measuring device and acting to limit said further axial advancing movement of the mandrel whereby the tube wall is thinned a preselected measured amount and said portion of the tube is circumferentially enlarged sufficiently to give it the preselected tightness in its tube-hole.

15. 21. The method of applying and controlling a progressively-applied rolling pressure, acting simultaneously on several angularly spaced areas of the inner surface of a lineal portion of a tube, so that the rolling pressure acts to thin the tube wall a preselected measured amount and thus circumferentially enlarge said portion of the tube to give it a preselected tightness in its tube-hole, which comprises applying, at a given rate, a torsional force to produce the rotating-force 20 component of said rolling pressure, applying, at a given rate, a separate linear force, acting axially relative to said tube, transmitted by means developing a proportional normal component to produce the radial-force component of 25 said rolling pressure, detecting the increase in the linear force, producing the increase in said radial-force component of said rolling pressure, which occurs the instant the tube portion is expanded sufficiently to bring several angularly 30 spaced areas of the tube outer surface into firm contact with the defining wall of its tube-hole, and then measuring and limiting the further displacement of said linear force which thus measures and limits the proportional further 35 displacement of said radial-force component of said rolling pressure whereby said tube wall is thinned the preselected measured amount.
